FRANCES W. ROLLER, OF ST. PAUL, MINNESOTA

COMBINATION HOSE SUPPORTER AND WAIST-ENCIRCLING GARMENT

Application filed October 6, 1930. Serial No. 486,537.

This invention relates to hose supporters and a combination girdle and hose supporter.

It is an object of my invention to provide a simple and improved hose supporter associated with a garter belt, girdle or other abdomen-encircling garment which will efficiently support the hose from front and rear and which will afford freedom of movement of the body and limbs to adapt it for use without restraining the wearer.

More specifically it is an object of my invention to provide a hose supporter associated with an abdomen-encircling garment having elements for clasping or engaging the front and rear or side portions of the tops of the hose and provided with simple and efficient means for equalizing the strains placed upon the engaged portions of the hosiery during various positions of the body of the wearer, such as while walking, sitting or bending.

It is a further object to provide a combination girdle and hose supporter so associated with the engaged portion of the hose that the lower edges of the girdle will be prevented from bulging or disfiguring the appearance of the wearer when the wearer is bending, walking or otherwise moving the limbs and torso.

Another object is to provide a combination girdle and hose supporter of neat, ornate appearance, compact in form, comfortable and adapted for manufacture at relatively low cost.

These and other objects and advantages of the invention will be fully set forth in the following description made in connection with the accompanying drawing, in which like reference characters refer to similar parts throughout the several views, and in which:—

Fig. 1 is a front perspective view of an embodiment of my invention applied to a girdle;

Fig. 2 is a perspective view showing the combination girdle and hose supporter as it appears when worn;

Fig. 3 is a fragmentary perspective view showing the manner in which the equalizing

cord is slidably mounted in the hem portion disposed at the lower edge of the girdle or encircling garment;

Fig. 4 is a detailed view illustrating one form of adjustable clasp or buckle for securing the ends of the equalizing cord, and

Fig. 5 is a fragmentary cross section taken on the line 5—5 of Fig. 1.

In the embodiment of the invention illustrated my device is associated with a slip-over or endless type of girdle, which as shown, comprises front and back sections 6 and 7 respectively, preferably constructed from stout flexible fabric and connected together by means of elastic side sections 8 which may be constructed from strong elastic webbing. As shown, an inverted V-shaped insert 9 of elastic webbing is provided in the lower edge of abdomen-supporting or front section 6.

At the inner lower edge of the girdle or waist-encircling garment an equalizing garter-supporting cord 10 is slidably mounted, said cord extending substantially circumferentially of the garment and as shown being guided and disposed within a series of tubular hem sections which also extend circumferentially of the inner and lower edge of the garment. In the embodiment illustrated an elongated hem section 11 is stitched or otherwise secured to the inner surface and lower edge of the back section 7, a pair of short spaced hem sections 12 are secured to each of the elastic side sections 8 of the girdle and a pair of spaced hem sections 13 are secured adjacent the lower edge of the front section 6 of the girdle. The equalizing cord 10 is

preferably, though not necessarily constructed of elastic material of circular cross section and has the two ends 10a and 10b which may be adjustably secured together at the front of the garment by suitable means, such as a clasp or buckle 14. If desired, the buckle can of course be eliminated and the ends tied together in properly adjusted position. The buckle as shown comprises a metal plate having a pair of spaced recesses 14a, the recessed portions having at their outer edges, teeth or corrugations for engaging the ends of the cord to retain the same against slippage. Buckle 14 may be conveniently encased

in a suitable pocket provided beneath the inverted V-shaped insert 9 by the addition of a small sheet of material 9a which may be stitched to the front section 6 having its lower edge free for insertion of the clasp or buckle and ends of the elastic cord.

Portions of the equalizing cord 10 depend from the lower edge of the girdle or encircling member between the respective hem sections or between portions of said hem sections, forming loops for supporting the garters. As shown, two of said loops numbered 15 depend in spaced relation from the lower edge of the rear girdle section 7 leaving therebetween a substantial portion of the tubular hem section through which the cord passes. The loops 15, it will be seen, are positioned above the rear portion of the thighs of the legs. A second pair of garter-supporting loops numbered 16 depend from the lower edge of the front girdle section 6 in substantially vertical alignment with the front thigh portions and between the two hem sections 12 at each of the side sections of the girdle a depending garter-supporting loop numbered 17 is formed aligned with the sides of the legs or thighs. A slide runner 18 is mounted on each of the depending loop portions of the cord, as shown, comprising a supporting member having a curved eye through which the cord is passed and having a slotted portion 18a to which the web of a hose-engaging clasp or fastener 19 is secured. The hose clasp may be of any suitable type, such as the conventional clamp illustrated, embodying a slotted clasp member and a button or stud for engagement with the same.

In use the encircling garment which may comprise a garter belt, girdle or other waist-encircling band is slipped over the hips or otherwise secured about the waist and the several hose-engaging clasps are connected with the upper edge of the stockings. In the embodiment illustrated the hose clasps on the depending loops 16 are connected with the front portions of a pair of stockings, while the clasps on the rear members 15 are engaged with the rear portions of said stockings and the clasps on depending loops 17 are connected with the side portions of the hose. If the equalizing cord 10, as is preferable, is constructed of elastic material, the same will be stretched to some extent in applying the hose clamps, as is clearly illustrated in Fig. 2. The stockings will thus be efficiently supported from side, rear and front portions.

It will be seen that the wearer of my garment may stoop, walk or flex the legs or torso without increasing or varying the strain upon any of the looped portions of the hose supporters and consequently without varying the strain upon the upper portions of the stockings engaged. This is true for the reason that the equalizing cord 10 may readily slide circumferentially of the several tubular

guides or hem sections to equalize for bending and flexing movements. When the wearer sits down, with the legs bent of course at an angle to the torso, the loops 15 at the rear of the encircling member will automatically be adjusted and will be lengthened as desired, while the loops 16 at the front of the girdle will be similarly shortened. Likewise, if the torso is bent to one side or the other, compensation in the lengths of the side loops 17 will be effected. This equalizing function clearly adds to the comfort of the wearer and prevents distortion of the girdle and the excessive strains to which the engaged portions of the stockings connected with most hose supporters are subjected. In bending or stooping the greatest equalization of course is required and this is taken care of for the most part by the sliding of the portions of the equalizing cord between the front and rear sections of the girdle. In the equalization between loops 17 the front and rear portions of the equalizing cord may move in the guides or hem portions and it will be noted that several inches of clearance is provided about the clasp 14 at the front edge of the girdle to enable this portion of the cord to slide freely for the requisite distances required.

In addition to the advantages and functions previously described it will be noted that with my device the lower edge of the girdle is yieldingly held down and prevented from rolling or bulging by the slidable engagement of the equalizing cord with the hem or tubular portions. Were it not for the equalizing cord this would not be true for in bending the tension would otherwise be released from at least a number of the loops. Attention is particularly called to the elongated hem or tubular portion at the rear edge of the girdle or encircling member which is engaged by the equalizing cord. With most corsets or girdles when the wearer stoops, an unsightly bulge occurs at the rear and lower edge of the girdle. This is entirely obviated by the combination of my equalizing cord and the substantial hem portions at the rear of the girdle.

From the foregoing description it will be seen that I have provided a simple, ornate and highly efficient hose-supporter and waist-encircling garment adapted to be manufactured at low cost.

It will further be seen that while I have shown a combination girdle and hose supporter, my invention is equally applicable upon garter belts, corsets and any other band or garment encircling a lady's waist.

It will, of course, be understood that various changes may be made in the form, details, proportions and arrangement of the parts without departing from the scope of my invention, which, generally stated, consists in a device capable of carrying out the

objects above set forth and in the novel parts and combinations of parts disclosed and defined in the appended claims.

What is claimed is:—

1. In combination with a waist encircling garment, such as a girdle, tubular guiding means disposed circumferentially of the entire garment at the lower edge thereof, an annular equalizing garter-supporting-cord connected to form an endless element extending through said tubular guiding means and freely slideable circumferentially of the garment, said guiding means having openings therein, said equalizing cord being considerably longer than the circumference of the garment and having loop sections depending from the openings in said guiding means and constituting garter supports and a series of hose clasps each mounted upon and freely slideable upon one of said loops.
- 15 2. In combination with a waist encircling garment such as a girdle, a broken hem disposed circumferentially of the entire garment at the lower edge thereof and constituting guiding means, said hem having a substantially unbroken portion traversing the rear of said garment having broken portions at the opposite sides of said garment and having a pair of broken portions adjacent the front of said garment disposed above the thighs of the legs of the wearer, an annular elastic equalizing garter-supporting-cord extending through said hem and connected to form an endless element freely slideable circumferentially of the garment, said equalizing cord being considerably longer than the circumference of the garment and providing loop sections depending from the said openings in the hem and a series of hose clasps
- 20 each mounted upon and freely slideable on one of said loops, the portion of said cord extending through the unbroken rear portion of said hem constituting means for yieldingly holding the rear edge of the garment downwardly to prevent bulging of the material when the wearer bends.
